United States Patent Office.

ENOCH S. YENTZER, OF OTTAWA, ILLINOIS.

Letters Patent No. 96,180, dated October 26, 1869.

IMPROVEMENT IN ATTACHMENT FOR SEWING-MACHINE.

The Schedule referred to in these Letters Patent and making part of the same.

To all whom it may concern:

Be it known that I, ENOCH S. YENTZER, of Ottawa, in the county of La Salle, and State of Illinois, have invented a new and improved Seamer; and I do hereby declare that the following is a full, clear, and exact description thereof, reference being had to the accompanying drawings, making part of this specification, in which—

Figure 1, plate 1, is a perspective view of my improved instrument, adapted for use upon the cloth-plate of a sewing-machine.

Figure 2, plate 1, is a top view of the instrument.

Figure 3, plate 1, is a front edge view of the instrument.

Figure 4, plate 1, is an enlarged view of the turning-devices.

Figure 5, plate 1, are views of a turning-device, differing somewhat from the turning-device of figs. 1, 2, and 3.

Figures 6 and 7, plate 2, are views showing the single-lapped seam, with one raw edge exposed.

Figures 8 and 9, plate 2, show the improved double-lapped seam.

Similar letters of reference indicate corresponding parts in the several figures.

The object of this invention is to produce a double-lapped seam, hereinafter described, by sewing-machinery.

To enable others skilled in the art to understand my invention, I will describe its construction and operation.

In figs. 6 and 7, plate 2, I have represented two pieces, 1 2, of cloth, united at their edges by lapping or turning a narrow portion, 7, of the edge of the piece 2 over the edge 6 of the piece 1, and then stitching through the three thicknesses of cloth. In this way one raw edge is enclosed by the lapped portion.

The raw edge of the lapped portion 7 may be left exposed, as shown, or this edge may be turned under and stitched down, as will be hereinafter explained.

Previous to turning or lapping the portions 7, and after the piece 1 has been properly adjusted upon the piece 2, with the wrong sides of the two pieces together, they should be basted so as to keep them smooth, and to preserve a uniformity in width of the seam.

The two pieces, 1 and 2, having been stitched together at 3, the top piece 1 is turned over the lapped portion 7, as shown in figs. 8 and 9, and stitched at 4 through four thicknesses of cloth.

A seam thus produced will have both raw edges of the pieces 1 and 2 closed, and will expose two rows of stitching on the right side of the cloth, which is the bottom side in fig. 8.

If the raw edge 7 of the piece 2 is turned under and stitched, as above stated, and a row of stitching is made along the folded part, so as to stitch this part

to the piece 2, a seam will be produced which will have the appearance, on the right side of the cloth, of a narrow covering-strip stitched along both edges.

The seam which I have above described can be conveniently and rapidly produced upon the cloth-plate of a sewing-machine by the attachment to such plate of an instrument constructed as shown on plate 1 of the accompanying drawings.

A represents the base-plate of the instrument, which has a slot, *a*, through one portion, through which the screw passes that is used to secure the instrument upon the cloth-plate of a sewing-machine. A long, narrow tongue or guide, *a'*, is also formed on this plate A, which may be marked off for indicating the widths of seams which it is desired to make.

B represents a follower, which is perforated at *b'*, to allow the needle to play through it, and which is formed on a narrow spring portion *b*, that is secured permanently to the surface of the plate A, in the position in figs. 1 and 2. This plate B is arranged so that the presser-foot of the sewing-machine will hold it down upon the work, and so that when the presser-foot is raised, the plate will spring up free from the cloth.

C represents a spring-turner, which is used for turning under the raw edge of the lapped portion 7 of the strip 2, as above described.

When it is not required to turn under the edge of this lapped portion 7, a simple guide, as shown in fig. 5, may be used in place of the turner.

The free end of this guide is curved under so as to form a small lip.

The free end of the turner C is curved, as shown at *c*, figs. 1 and 3.

That end of the turner which is secured to the plate A by a thumb-nut, G, and fixed screw-thread, *g'*, is slotted at *e* to allow of its adjustment for seams of different widths.

Instead of slitting the shank of the turner C longitudinally, as shown in figs. 1 and 2, this shank may be slotted or notched transversely, as shown at *v*, fig. 5, to receive the screw-stud *g'*, and perforated at *v'* to receive a fixed stud, *g*.

The latter construction is best, for the reason that it admits of the detachment of the turner from the instrument without removing the nut G.

The turning-lip *c* is arranged between the follower-plate B and the lapping-lip *d*. This lapping-lip *d* is curved in a direction opposite to the curve of the lip *c*, and forms, in conjunction with the lip *c*, a slot through which the work is drawn on its way beneath the needle.

The lip *d* is formed on an adjustable gauge-plate, D, which is slotted at *d*, and secured in place by the thumb-nut G.

The gauge *s* lies transversely across the narrow

graduated tongue a' of the plate, and is formed on the narrow extension s of the plate D , as clearly shown in the drawings.

On that edge of the plate D which is next the turner C , and protruding transversely from the curved shoulder of the lapping-lip d , is a narrow guide, t , which extends across the tongue a' , and beneath the follower-plate B .

This guide, t keeps the lapped portion of the cloth in its proper place with respect to the needle at the point where the stitches are formed.

In fig. 4, of plate 1, I have represented the instrument in the act of lapping and turning the edge of one piece, 2, of cloth over the edge of a piece, 1, for producing a seam representing a narrow piece stitched on the cloth.

For a simple seam, such as is represented in figs. 6 and 7, the turner C , shown in figs. 1, 2, 3, and 4, is not used.

While I prefer to employ the instrument herein described for producing the improved lapped seam, I do not confine myself to the precise construction of

this instrument, as the turning and lapping-devices may be varied in their construction.

The gauge s' , lying across the graduated tongue a' , serves as a convenient means for indicating the width of space between the turning-lips or hooks, so that the instrument can be quickly and accurately set for a seam of any given width.

What I claim as new, and desire to secure by Letters Patent, is—

1. An instrument for producing the seam herein described, consisting of parts A , a' , B , D , d , and s' , constructed so as to operate substantially as set forth.

2. The adjustable lapping-hook d and turner or guide C , combined with a gauge, s' , substantially as described.

3. The lapping-hook d , the turner or guide C , the guide t , and the follower-plate B , constructed and combined substantially as described.

ENOCH S. YENTZER.
